PORTABLE TRAFFIC CONTROL DEVICE

Roy E. Wilson, Clarion, Iowa, John P. Kistle,
Minneapolis, Minn., and Albert H. Tracy, San
Antonio, Tex.

Application November 26, 1948, Serial No. 62,052

5 Claims. (Cl. 177—329)

1

This invention relates to portable traffic control devices. At the present time many emergency situations arise on highways which require the control of traffic by peace officers and others to prevent accidents from occurring. Many of these emergency conditions arise through a first accident, a fire, a traffic block as when road repairs are being made, or when an examination of all traffic within a certain area is to be made to apprehend a criminal known to be in that area. It is highly desirable that there be provided for use by peace officers and others a portable traffic control device which can be carried in an automobile and can be very quickly set up for use to control traffic in emergency situations.

It is an object of the present invention to provide such a device which is of cheap and simple construction and which can be effectively used to slow or stop traffic, particularly at night, and warn of the emergency situation.

The objects and advantages of the invention will more fully appear from the following description made in connection with the accompanying drawings, wherein like reference characters refer to the same or similar parts throughout the different views, and in which:

Fig. 1 is a perspective view of a portable traffic control device embodying the invention collapsed and ready to be transported;

Fig. 2 is a view in front elevation of the device in extended condition set up ready for use;

Fig. 3 is a horizontal section taken on the line 3—3 of Fig. 2 as is indicated by the arrows;

Fig. 4 is a vertical section taken substantially along the irregular line 4—4 of Fig. 2 as is indicated by the arrows;

Fig. 5 is a vertical transverse section through the device when in collapsed condition.

Fig. 6 is a horizontal section through portions of one of the standards taken on the line 6—6 of Fig. 5 as is indicated by the arrows, the view being in enlarged scale;

Fig. 7 is a vertical section in enlarged scale taken on the line 7—7 of Fig. 2 as is indicated by the arrows; and

Fig. 8 is a wiring diagram of the device.

In accordance with the invention, there is provided a rectangular base plate 9 having secured by hinges 10 thereto at opposite sides thereof a pair of half casings 11 which can be swung upwardly from the base plate 9 as shown in Figs. 1 and 5 to bring the edges of the half casings into abutment and form with said base plate a carrying case. Cooperating fastening elements 12 are provided adjacent the joining top edges of

2

the half casings, as the carrying case is considered when it is closed, to retain the carrying case in closed condition and one of the half casings is provided with suitable handle 13 to permit the entire device to be readily carried.

5 Mounted on the base plate 9 are a pair of oppositely disposed telescopic standards, each designated as an entirety by the letter A. Each standard A includes a lower tubular section 14 screwed or otherwise secured to a socket 15 carried by the upper side of the base plate 9. Telescopically received within the lower section 14 for extension therefrom is an intermediate section 16, also preferably of tubular formation, while telescopically received within the intermediate section 16 for extension therefrom is an upper telescopic section 17. The upper ends of the lower section 14 and the intermediate section 16 are swedged inwardly at 14a and 16a, respectively, to cooperate respectively with outwardly swedged lower end portions 16b and 17b of the respective sections 16 and 17, thereby preventing complete removal of the section 16 from the section 14 and of the section 17 from the section 16. The section 14 and the section 16 are each provided with indented portions 14c which cooperate with shoulders produced respectively by the swedging of the lower ends of the sections 16 and 17 to normally prevent the extension of the section 16 from the section 14 beyond a certain point and to prevent extension of the section 17 from the section 16 beyond a certain point. The section 16 carries near but spaced upwardly from its lower end a cross tube 18 within which is located a coil spring 19 bearing at its two ends against the heads of a pair of headed catch pins 20 which work within small openings provided in the wall of the section 16, these pins acting as stops when the section 16 is fully extended from the section 14 to cooperate with the swedged portion 14a of the section 14 and prevent the downward telescoping of the section 16 until these pins are pressed inwardly as by the fingers of the operator. In similar manner, the upper section is provided with spring pressed stop pins 21 and associated parts which prevent the downward telescoping of the upper section 17 within the intermediate section 16 unless extended after the upper section 17 has been extended from the intermediate section 16. The intermediate sections 16 are made of somewhat greater length than the lower sections 14.

The upper sections 17 are equipped with outwardly extending ears 22 at the forward side of the device which ears, if desired, may be punched

outwardly from the tubing forming these upper sections 17. Pivot pins 23 are received in each pair of ears 22 and journaled on these pivot pins are ears 24 formed on a pair of arms 25 which may be of tubular formation. These arms 25 are in turn interconnected at their upper ends by a cross bar 26 which centrally carries a light designated as its entirety by the letter B. The said light may include an interiorly screw threaded electric bulb socket 27 centrally welded or otherwise secured to the bar 26 and to this socket is attached a parabolic reflector 28 carrying a glass 29. Within the socket 27 there is received first a thermostatic flasher 30 and then an electric light bulb 31, it being understood that the flasher 30, the details of which are not shown, will act to intermittently through thermostatic action break and make any circuit to the bulb 31 when the bulb is lit. Extending between the two arms 25 is a sign 32 carrying suitable printing matter 33 thereon, such as the word "Stop." This sign 32 is located below the light B so it can be readily seen below the same. The two upper sections 17 of the telescoping standards A are equipped with cross slots 17a just below the ears 22 to slidably receive any one of a number of signs 34 which will carry printing matter 35 on both sides thereof, such as appropriate to the occasion. Thus, on one side of the sign 34 such words as "Sheriff," "Police," "Fire," etc., may be printed, while on the other side of this sign such words as "Slow" may be printed.

The two arms 25, the cross bar 26, the sign 32, and the light B may all be swung downwardly about the pivot pins 23 so that the two arms 25 lie closely adjacent the standards A with the light B between the two standards as shown in Fig. 5, or, if desired, the said parts may be swung upwardly from the upper sections 17 so that the arms 25 in effect form continuations of the two standards A. To hold the arms 25 in the upwardly extending position the arms are equipped near their lower ends with U-shaped spring clips 36 having the general shape of bicycle trouser clips and these clips will receive upper portions of the upper sections 17 as the arms are swung upwardly therefrom.

Mounted on the base plate 9 are a pair of keepers 37 within which oppositely disposed sliding bolts 38 are mounted and these bolts may be extended laterally from the hinged edges of the base plate 9 to overlie the main panels of the half casings 11 when they are downwardly swung to horizontal position, and the bolts are adapted to be received within keepers 39 mounted on the said panels and the bolts may thus be used to retain the two half casings 11 in extended position. Mounted on the inner sides of the panels of each half casing 11 are a pair of headed rods 40 on which battery holding hooks 41 are mounted, these hooks being engageable with screws 42 also carried by the main panels of the half casings 11. Batteries 43 of the hot shot dry cell type are adapted to be carried by the half casings 11 through the medium of the said battery holders consisting of the rods 40, hooks 41, and screws 42. Also secured to the base plate 9 is a three pole electric switch 44 and one wire 45 extends from one of the fixed contacts 44a of this switch to the left hand battery 43 as viewed in Figs. 3 and 8, 70 and another wire 46 extends from one of the other fixed contacts 44b of this switch to the right hand battery 43 as viewed in Figs. 3 and 8. Another wire 47 runs from the movable contact 44c of the switch 44 to connect with one contact of

the socket 27 of the light B, the other contact of the socket being grounded. The switch 44 also includes a fixed contact 44d with which the movable contact 44c may be engaged, but no wire runs from the contact 44d, and accordingly, no circuit will be established from either battery 43 to the light B when the movable contact 44c is engaged with contact 44d.

Normally, the device will be retained in collapsed condition as shown in Fig. 1 and in Fig. 5 with the telescoping standards A collapsed within the carrying case as shown and with the arms 25 and light B swung downwardly as is indicated and with the cooperating fastening elements 12 engaged. In this condition the device can be very easily handled and transported as in an automobile by a peace officer such as a policeman, a sheriff, or the like, ready for emergency use when the occasion arises. When an emergency situation occurs requiring the control of traffic as at an accident, fire, or the like, the peace officer arriving at the scene of the emergency can quickly open up the carrying case by releasing the cooperating fastening elements 12, whereupon the two half casings 11 will be swung downward to a horizontal position as is illustrated in Figs. 2, 3, and 4, and the bolts 37 can be extended to lock the half casings in this position. Thereupon, the arms 25 may be swung upwardly to cause the 25 spring clips 36 to engage the upper sections 17 of the two standards and by grasping the cross bar 26 and pulling it upwardly, the intermediate telescoping sections 16 may be extended from the lower sections 14, and the upper telescopic sections 17 may be extended from the intermediate sections 16. The movable contact 44c of the three pole switch 44 may be then swung to engage it with one of the fixed contacts 44a or 44b, whereupon a circuit will be established from the selected 30 battery 43 to the bulb 31 and the device will be set in operation and the bulb 31 will be intermittently lit to give a flashing signal from the light B. Preferably, the glass 29 will be colored red to indicate danger. Of course, as the intermediate and upper sections 16 and 17 of the two standards are fully extended, the catch pins 20 and 21 will be forced outwardly to prevent dis- 35 tension of the standards A. The two batteries 43 being quite heavy will act as weights to retain the portable traffic control device upright in the ex- 40 tended position. The sign 34 carrying the desired printing matter will normally be already inserted in place within the slots 25a before the device is put into use, and accordingly, the printing matter 45 on both signs 32 and 34 will be displayed in a prominent position to be read by the drivers of all vehicles approaching the emergency situation on the highway. The flashing light will give 45 warning of the emergency situation well in advance of the point of emergency and vehicle traffic will accordingly be warned and will come to a stop. After the vehicles have stopped, the peace officer can direct traffic as required. Usually, two 50 of the traffic control devices will be employed on a highway, one at either side of the emergency situation facing in opposite directions and cars approaching and passing a first one of the devices in one direction at night will be enabled to read the rear printing on the sign 34 on the other device to proceed according to the directions on that sign. The printed matter 33 and 35 on the two signs will preferably be made of a reflective type of material so that this printed matter will stand out well to be easily read. Obviously, the 55 device can be very easily set up and, of course,

it can be readily collapsed when the emergency is over. The two batteries 43 are provided and the three pole switch 44 is employed so that either battery can be used to establish the circuit to the light, whereupon if one battery wears down the other battery can be employed.

It will, of course, be understood that various changes may be made in the form, details, arrangement, and proportions of the various parts without departure from the scope of the present invention, which, generally stated, consists in the matter shown, and described, and set forth in the appended claims.

What is claimed is:

1. A portable traffic control device comprising a base plate, a pair of half casings hinged to opposite edges of said base plate and swingable upwardly therefrom to abut and form with said base plate a carrying case, a battery carried at the inside of one of said half casings and swingable downwardly with the same to weight the lower portion of the device, a pair of telescoping standards mounted in upstanding relation on said base plate to be disposed when distended within said case when the case is closed and adapted to be extended when the case is open to points well above the level of said base plate, a cross bar carried by the upper portions of said standards, a light mounted on said cross bar, a sign carried by the upper portions of said standards below said light, and an electric circuit adapted to be established from said battery to said light.

2. A portable traffic control device comprising a base plate, a pair of half casings hinged to opposite edges of said base plate and adapted when swung upwardly to form with said base plate a carrying case, a battery mounted on the inner side of one of said half casings and adapted to be swung downwardly with the half casings to weight and stabilize the device, a pair of arms pivotally connected respective to the upper portions of said standards for swinging movement downwardly alongside the said standards to fit within said carrying case when the standards are distended and for extension upwardly above said standards when the standards are telescopically extended, means for retaining said arms in upwardly swung position, a cross bar carried by said arms, a light mounted on said cross bar, a sign carried by the two arms adjacent said light, and an electric circuit adapted to be established from said battery to said light.

3. A portable traffic control device comprising a base plate, a pair of half casings pivoted to opposite edges of said base plate and adapted when upwardly swung from said base plate to be brought into engagement to form with said base plate a carrying case, battery holders carried by said half casings at their inner sides, latches mounted for cooperative action between said base plate and said half casings to hold said half casings in downwardly swung position extended from the sides of said base plate, a pair of telescoping standards mounted on said base plate and adapted when distended to fit within the case when closed and adapted to be raised in extended position to a level well above said base plate, a pair of arms pivotally connected to the upper ends of said standards, a cross bar extending between said arms, a light carried by said cross bar, a sign below said light carried by said arms, said arms, cross bar, and light adapted to be swung downwardly adjacent said standards to fit within said case when the standards are distended and the case is closed, and adapted to be swung upwardly above said standards, means for cooperation between said arms and the upper ends of said standards for retaining the arms in upwardly swung position, and electric wiring for establishing an electrical circuit from a battery held within one of said battery holders to said light.

4. The structure defined in claim 3, each of said standards including a plurality of telescopic sections and means for releasably retaining the sections of the standards in extended position as the standards are fully extended.

5. The structure defined in claim 4, said light including a flasher for intermittently interrupting and reestablishing the circuit to the light.

ROY E. WILSON.
